WITNESS:

R. E. L. Leal

INVENTOR
BY *Victor J. Evans*

ATTORNEY

UNITED STATES PATENT OFFICE

FRANCISCO LEAL, OF SAN DIEGO, CALIFORNIA

ADVERTISING DEVICE

Application filed January 3, 1928. Serial No. 244,266.

This invention relates to advertising and is an improvement on the advertising device forming the subject matter of my application filed April 30th, 1927, Serial No. 187,902.

A general object of the present invention

5 is to provide an advertising device for public conveyances, such as street cars, railroad passenger cars, busses and the like, and said device is to be used in combination with the advertising card holders now employed, with 10 no change to the holders.

A further object of the invention is to provide an advertising device of the character set forth, that is capable of receiving advertising cards and the like, in an easy and expeditious manner, and so that they can be displayed to attract the attention of a casual observer.

Another object of the invention is to provide an advertising device that is extremely 20 simple in construction and is inexpensive to manufacture.

This invention also consists in certain other features of construction and in the combination and arrangement of the several parts, 25 to be hereinafter fully described, illustrated in the accompanying drawings and specifically pointed out in the appended claim.

In describing my invention in detail, reference will be had to the accompanying drawings 30 wherein like characters denote like or corresponding parts throughout the several views, and in which:

Figure 1 is a perspective view of the device 35 forming the subject matter of the present invention and showing its application to the advertising card holders now generally employed in public conveyances.

Figure 2 is a sectional view taken on line 40 2-2 of Figure 1, looking in the direction of the arrows.

Figure 3 is a fragmentary sectional view 45 taken on line 3-3 of Figure 2 looking in the direction of the arrows and showing the device in open position.

Figure 4 is an enlarged fragmentary perspective sectional view taken through a portion of the device as shown in Figure 3.

Referring to the drawings in detail the 50 letter A indicates a portion of the side of a

public conveyance and which includes the usual advertising card holding means which has a curved card receiving surface B with flanged guides C disposed to engage the edges of cards in the usual manner.

The device which forms the subject matter 55 of the present invention is adapted to be fixed to the upper and lower flanged guides through the instrumentality of screws 1 and said device comprises sheets of material which may be of any length disposed in end to end relation or the sheets may be of a length to extend the entire length of the vehicle as suggested in Figure 3. The screws 1 secure said sheets in confronting relation with the card receiving surface as best shown in Figure 1 of the drawings. The sheets of material are formed from metal and have closed portions indicated by the reference numeral 2 and open portions 3 in the form of a frame as best shown in Figure 3.

60 The sheets have their lower ends bent upwardly upon themselves to provide a channel shape guide 4 for the purpose of receiving an advertising card 5 in the closed portions 2 and a transparent member 6 in the open portions 3, and these cards and transparent members are retained in the guides 4 by strips 7 hingedly secured to the top of the sheets and held in operative position as shown in Figure 1 through the instrumentality of 65 coil springs 8.

The card receiving surface B is adapted 70 to have secured thereto lamp sockets 9 for receiving lamps 10 which of course are in connection with a suitable source of current, and these lamps 10 are only disposed to the rear of the transparent member 6 so that the advertising matter on the transparent members can be readily seen.

75 The strips 7 are further provided with a centrally disposed outwardly flared portion 11 in order to provide a finger engaging surface for the purpose of disposing the strips to open position against the tension of the coil springs 8 thereof and these flared portions 90 11 overlie the screws 1 of the closed portions. It will be noted that the screws 1 are disposed through the strips of the open portion for the purpose of securely holding the 95 100

transparent members in operative position as it will be apparent that the transparent members are considerably heavier than the advertising cards 5. When it is desired to remove the transparent members, the screws 1 for the strips thereof must be removed, but the cards can be removed by merely lifting their strips against the tension of the coil springs 8.

- 10 Held in operative position by the guides 4 and the strips 7 are the usual flexible strips 12 for covering the edges of the cards and transparent members as best shown in Figures 1 and 3 of the drawings.
- 15 The advertising matter supported by or on the transparent members can be of any character such as letters and figures cut from card board, wood or the like, and the cut out portions may be covered with colored semi-transparent material so that it can be illuminated by lamps of any desired color, arranged and operated in any desired manner. For example, the lamps may be arranged and operated to produce a still picture in an advertisement or give the appearance of one in motion.

From the above description and disclosure of the drawings, it will be obvious that I have provided an advertising device for street cars and the like, that can be associated with the card holders now employed therein or it can be provided in cars at the time of their manufacture, in which event the flanged guides C would be dispensed with, and my device supports advertising matter in a manner so that it will attract the attention of a casual observer.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

An advertising device of the character described comprising sheets adapted to be secured at an inclination, and having closed and open portions, guide flanges formed with the bottom of said sheets, spring pressed strips secured to the upper ends of said sheets and cooperating with the guide flanges to hold advertising cards and advertising transparent members in operative position with respect to the closed and open portions, means for illuminating the transparent members, and flexible strips covering the confronting edges of the cards and transparent members.

In testimony whereof I affix my signature.

FRANCISCO LEAL.
